PLASTER LATH

Filed July 3, 1923

Inventor:
OLE CARLSON
By *Hagard & Miller*

Attorneys.

UNITED STATES PATENT OFFICE.

OLE CARLSON, OF LOS ANGELES, CALIFORNIA, ASSIGNOR OF ONE-HALF TO C. F. WESTBURG, OF LOS ANGELES, CALIFORNIA.

PLASTER LATH.

Application filed July 3, 1923. Serial No. 649,252.

My present invention is a plaster lath, and it is a special object of this invention to provide a plaster lath adapted to be made from thin boards, which may be of varying width but which are preferably of a standard length, such as thirty or thirty-six inches, although odd lengths are entirely suitable for some of the uses to which my plaster lath is especially adapted.

It is an object of this invention to provide a novel plaster lath which may optionally be made from stock which would otherwise go to waste, my plaster lath being especially suitable for economical use when lathing is to be applied directly upon a flat surface, without provision for air space between my plaster lath and the said surface.

Although my invention has unique advantages adapting it to use upon preexistent perfect or imperfect flat surfaces, it should be understood that my plaster lath is a highly advantageous form of lathing for use in any ordinary building construction, in which separate wooden laths or expanded metal lathing, or the like, have heretofore been used, both of my herein shown constructions being such as to provide a strong and flexible foundation, suitable for use upon either regular or irregular surfaces, and requiring a minimum quantity of plaster in order to form a satisfactory "key", for securing the plaster in place; and in a preferred construction I provide my plaster lath not only with staggered slots, which need not be undercut, but also with round holes, which are preferably undercut, in order to provide a sufficient and suitable key for the plaster secured thereby.

Other objects of my invention will appear from the following description of two preferred embodiments thereof, and from the appended claims, taken in connection with the accompanying drawings, in which—

Fig. 1 may be regarded as a back elevation of one form of plaster lath embodying my invention.

Fig. 2 is a longitudinal section on the line 2—2 of Fig. 1.

Fig. 3 is a transverse sectional view showing how a key may be formed when the plaster lath of Figs. 1 and 2 is used upon ordinary studding or where an air space is to be provided.

Fig. 4 is a similar view, showing how my

plaster lath may be employed directly upon a flat surface of wood, or the like.

Referring in detail to the parts of that specific embodiment of my invention shown in Figs. 1, 2, 3 and 4, 1 being a plaster lath of any desired dimensions, such as ten by thirty-six inches, and a quarter of an inch, more or less, in thickness, 2 are slits or slots, preferably extending approximately in the direction of the grain of the board from which my lath is formed, and 3 are additional circular openings cut through the said board, these openings being shown, in the present instance, as cut in the line of the slits or slots 2, and undercut or tapered or flared at 4 in the manner best shown in Figs. 3 and 4, in order to permit a spreading or keying of the plaster 5.

I am aware that a plaster lath has heretofore been formed by forming slots in boards, and I am aware that wood lath has also been formed by providing circular apertures in boards; but I obtain a novel and advantageous result by the conjoint use of slots and circular apertures, and I find it highly advantageous, from the standpoint of economy in the use of plaster, to undercut only the mentioned circular apertures, my described slots being adequate to prevent a lateral movement of the plaster relatively to a wall, and the undercutting of the circular apertures being sufficient to key the same against outward displacement. It will be understood that before plaster is applied to my novel plaster lath, the same should be thoroughly wet, in the manner well known to workers in this art.

Although I have herein described but two complete embodiments of my invention, it should be understood that various features thereof might be independently employed, and also that various modifications might be made without departure from the spirit and scope of my invention as the same is indicated above and in the following claims.

What I claim is:—

1. A lath formed of a board or equivalent homogeneous material having a series of parallel slots through the board from front to back, the slots of each series being spaced apart at their ends and each row being staggered whereby sufficient solid board is left to give strength to the lath, and a plurality of undercuts of partially conical form with the bases of the partial cones at the

back of the board and merging into each slot.

2. A wall structure comprising a flat back-
ing, a facing of laths secured directly there-
on, each lath being formed of a board or
equivalent homogeneous material having a
series of parallel slots through the board
from front to back, the slots of each series
being spaced apart at their ends and each
row being staggered whereby sufficient solid
board is left to give strength to the lath,

a plurality of undercuts of partially conical
form with the bases of the partial cones at
the back of the board and merging into each
slot, and with a coating of plaster on the
face of the laths, said plaster extending
through the slots and being keyed in the
partially conical undercuts of the slots in
the back of the boards.

In testimony whereof I have signed my
name to this specification.

OLE CARLSON.
